UNITED STATES PATENT OFFICE.

JAMES DUNLOP, OF CHICAGO, ILLINOIS, ASSIGNOR TO KAESTNER & HECHT COMPANY, OF CHICAGO, ILLINOIS, A CORPORATION OF ILLINOIS.

ELEVATOR.

Application filed March 12, 1925. Serial No. 14,857.

The present invention relates to improvements in elevators.

In industrial establishments where large or heavy loads are frequently to be carried by elevators, large freight elevators are needed. During most of the time, however, there is but little use for a large elevator, and a smaller elevator would be more desirable and economical. The primary object of the invention, therefore, is to provide a double unit elevator having two cages which can be operated independently, or operated jointly as desired.

In operating two cages as one, however, considerable difficulty is met in maintaining the two platforms at the same level, i. e. causing the cages to travel through a uniform distance at a uniform speed. Such a result is not only desirable, but is necessary for the successful and practical operation of such elevators. Another object therefore resides in the provision of novel means for mechanically connecting parts of the two elevator units, and means for synchronizing the operation of the driving means so as to cause the cages to travel through a uniform distance at a uniform speed.

A further object resides in the provision of means for connecting and disconnecting the two counterweights, and in the specific construction of said means.

Another object is to provide an elevator of the above character which is equipped with suitable interlocking means in the control circuits such that when the counterweights are connected the cages cannot be operated independently, and when the counterweights are disconnected the cages cannot be operated jointly.

A more specific object is to provide a novel elevator having two independent units, each of which comprises a cage, driving means for the cage, and a controller therefor, and which are adapted to be operated separately by means of their individual controller, or jointly by means of one of said controllers.

Ancillary objects and advantages will become apparent as the description proceeds.

In the accompanying drawings, Figure 1 is a vertical sectional view of an elevator hatchway for an elevator constructed in accordance with my invention.

Fig. 2 is a sectional view taken along line 2-2 of Fig. 1.

Fig. 3 is a sectional view taken along line 3-3 of Fig. 1.

Fig. 4 is a front view of the counterweights.

Fig. 5 is a side view of the counterweights.

Fig. 6 is a horizontal sectional view of the counterweights taken along line 6-6 of Fig. 4.

Fig. 7 is a sectional view taken along line 7-7 of Fig. 6.

Fig. 8 is an enlarged fragmentary front view of the locking members for the counterweights and the interlocking switches controlled thereby.

Fig. 9 is a diagrammatic representation of the control circuits for a double unit elevator embodying the features of my invention, the circuits being connected for joint operation.

While the invention is susceptible of various modifications and alternative constructions, I have shown in the accompanying drawings and will herein describe in detail the preferred embodiment, but it is to be understood that I do not thereby intend to limit the invention to the particular form disclosed, but aim to cover all modifications and alternative constructions falling within the spirit and scope of the appended claims.

In its exemplary embodiment, the invention contemplates the provision of two electric elevator units of which the cages are operable in a single hatchway and are adapted to be operated independently, or jointly as a single platform, means for locking the counterweights together for joint operation, and electric interlocks in the control circuits of the two elevator units for preventing independent operation of the cages and for synchronizing their movements when the counterweights are locked together, but permitting independent operation of the cages when the counterweights are disconnected from each other.

The elevator structure.

Referring to Figures 1 to 3, the hatchway comprises front and rear walls 10 and 11, and right and left side walls 12 and 13. The side walls are each built with suitable doors 14 at the different floors.

Mounted side by side in the hatchway are two elevator cages 15 and 16. Each cage

is provided with suitable guide shoes 17 at the front and rear engaging vertical guide rails 18 in the hatchway. The adjacent walls of the cages are provided with vertically sliding gates 19 which are adapted to be raised to permit the joint use of both platforms.

Mounted on a floor 20 at the top of the hatchway are two traction machines, one for each cage. While these machines may be of any suitable construction, in the present instance they comprise electrical motors 21 and 22 respectively which are provided with electromagnetic brakes 23 and 24, and which are directly geared to two traction drums 25 and 26 respectively. The latter are rotatably supported by pedestal bearings 27 which with the motors and the brakes are mounted on two base plates 28. Wound on the drums 25 and 26 are cables 29 and 30 respectively, the like ends of which are connected in one instance to the cages 15 and 16 and in the other instance to two counterweights 31 and 32 respectively. The counterweights are provided with suitable guide shoes 33 which engage two sets of vertical guide rails 34. These sets of rails are positioned in parallel and closely spaced relation to permit positioning the counterweights next to each other, and are supported centrally on the rear wall 11 of the hatchway to simplify the arrangement of the traction machines. In leading to the counterweights, the cables 29 and 30 are directed respectively over two sheaves 35 and 36 rotatably mounted in a box 37 just below the floor 20. Since the counterweights are mounted to move in closely spaced paths, one sheave is positioned below the other to avoid interference between the two. The base plates 28 of the traction machines are inclined diagonally with respect to the cages 15 and 16 and are arranged perpendicularly to each other to direct the cables downwardly, centrally of the cages and of the counterweights.

The counterweights.

Each of the counterweights 31 and 32 comprises a rectangular frame which consists of two spaced vertical channels 38 connected at the top and bottom by cross structures 39 and 40. The guide shoes 33 are secured to opposite ends of these cross structures. A plurality of weights 41 are loosely mounted between the channels 38 and over the cross structure 40, and are held in position by two binding rods 42 which extend between the cross structures and through aligned holes 43 in opposite ends of the weights. Tubular spacing sleeves 44 are positioned on the upper ends of the rods 42 and between the cross structure 39 and the uppermost weight 41. Upon changing the number of weights 41 on the counterweight, sleeves 44 of proper length are substituted. The construction of

the counterweights thus far described is old and well known, and forms no part of the present invention.

Adjustably mounted between the channels 38 of each counterweight is a cross head 70 which comprises an outer plate 45, and an inner plate 46. The inner plates of the two counterweights are located adjacent each other when the latter are positioned side by side. The inner and outer plates of each counterweight engage opposite legs of both channels 38, and are adapted to be clamped thereto by a plurality of bolts 47. These bolts extend through the plates next to the channels. Two heavy elongated blocks 48 extending between the channels 38 are secured between the plates 45 and 46 by bolts 49 extending through the latter, and are separated vertically by means of spacers 50 positioned between their opposite ends. The binding rods 42 extend loosely through holes provided therefor in the blocks 48 and the spacers 50. Two adjusting rods 51 connected to the upper cross structure 39 extend downwardly through aligned holes in the opposite ends of the blocks 48 and in the spacers 50, and are secured thereto by nuts 52 which permit the cross head to be vertically adjusted in the counterweight.

The blocks 48 of the two counterweights are formed on their adjacent sides with lateral projections 53 which extend through longitudinal slots 54 in the inner plates 46. Pivotally mounted on vertical pins 55 and between the blocks 48 in the counterweight 31 are two connecting or locking members 56. These members are adapted to be positioned completely within the counterweight 31 when the counterweights are disconnected, and are adapted to be swung into the horizontal space between the blocks 48 in the counterweight 32 to connect said counterweights for movement as a unit. To avoid difficulty in connecting the counterweights when slightly out of horizontal alignment the free ends of the member 56 are beveled. The pins 55 preferably are formed with enlarged portions 57 on which the connecting members 56 are mounted, and extend through the blocks 48 to which they are non-rotatably secured by nuts 58.

To provide suitable means for actuating the connecting members 56 the latter are formed with right hand and left hand gear quadrants 59 and 60 respectively which mesh with a worm 61 journaled in the outer and inner plates of the counterweight 31. One end of the worm shaft extends through the outer plate 45, and is provided with a squared end 62 to facilitate adjustment of the worm. The outer plate 45 is formed with two spaced openings 63 next to the quadrants 59 and 60 to permit the latter to project slightly beyond the blocks 48.

Mounted in the outer plate 45 and on the

upper block 48 of the counterweight 31 are two interlocking switches 64 and 65 each of which is provided with a movable contact member 66. The contact members 66 are adapted to be actuated by cam faces 67 and 68 formed on the upper edges of the quadrants 59 and 60 respectively. These cam faces are so arranged that when the locking members 56 are moved into engagement with the counterweight 32 the switch 65 will be opened and the switch 64 will be closed, and that when said members are positioned completely within the counterweight 31 the switch 64 will be open and the switch 65 closed.

The control circuits.

Referring to Fig. 9 two sets of control circuits, one for each elevator unit, connected by suitable interlocking switches for joint operation are shown. The position of each of the interlocking switches when the control circuits are disconnected for independent operation of the elevator units is illustrated in dotted outline. Since the two sets of control circuits are substantially alike only one will be described in detail, and the corresponding parts of the other will be designated by like numerals primed.

Each elevator unit comprises a car switch 69, consisting of a controller 70 and two contacts 71 and 72, which controls "up" and "down" directional switches 73 and 74 respectively. The directional switches each control a potential switch 75 and two accelerating switches 76 and 77 which are operable in timed sequence to progressively cut out resistance in two of the motor windings.

The wiring is best described by outlining the elevator operation. Assuming that the interlocking switches are in their dotted positions to permit independent operation of the elevator units, and that the controller 70 is moved into engagement with the contact 72, the following control circuit is established: from the main L^2 , through wire 78 passing through two gate switches 79 which are closed when the gates 19 are down, the counterweight switch 65 which is closed when the counterweights are disconnected, an interlocking switch 80, a fuse 81, a safety device 82, and an interlocking switch 83 to the controller 70; then through the contact 72, a wire 84 and a coil 85 of the "up" directional switch 73; and then through wire 86 passing through a plurality of safety devices 87, an interlocking switch 88 and a fuse 89 to the main L^3 .

Excitation of the coil 85 closes the switch 73 which establishes the following control circuits: from the main L^3 through a wire 90, switch contacts 91, and a wire 92 to the brake winding 23 and through resistances A and B to one winding of the motor 21;

from the main L^2 through a wire 93, switch contacts 94, and a wire 95 to the brake winding 23; and from the main L^1 through a wire 96, a coil 97 of the potential switch 75, the wire 95, the contacts 94 and the wire 93 to the main L^2 .

Excitation of the coil 97 effects a closure of the switch 75 which establishes the following control circuits: from the main L^1 , through the wire 96, switch contacts 98, and a wire 99 to the brake winding 23 and through resistances C and D to another winding of the motor 21; and from the main L^2 , through the wire 93, the switch contacts 94, the wire 95, switch contacts 100, and a wire 101 to the third winding of the motor 21. Upon the establishment of these circuits the brake 23 is released, and the motor 21 begins to operate to move the cage 15 in an up direction.

Shortly after the motor 21 begins to operate, a pair of switches 102 and 103 controlling the accelerating switches 76 and 77 respectively are closed in timed sequence and in the order named by any suitable means (not shown). Closure of the switch 102 completes the following circuit: from the wire 95, through the switch 102, and a coil 104 for the accelerating switch 76 to the wire 92. Closure of the switch 76 short circuits the resistances A and C in the wires 92 and 99 through switch contacts 106 and 107 respectively thereby accelerating the speed of the motor 21.

Subsequent closure of the switch 103 completes the following circuit: from the wire 95 through the switch 93, and a coil 108 for the switch 77 to the wire 92. Excitation of the coil 108 closes the accelerating switch 77 which short circuits the resistances B and D in the wires 92 and 99 through switch contacts 109 and 110 respectively, thereby increasing the speed of the motor 21 to full speed.

To stop the cage the controller 70 is moved into its neutral position, thereby breaking the control circuit through the coil 85, and returning all parts of the system to initial position.

Upon movement of the controller 70 into engagement with the contact 71, a control circuit through a wire 111 and a coil 112 for the "down" directional switch 74 is completed. The switch 74 when closed serves to connect the wires 92 and 95 through switch contacts 113 and 114 to the wires 93 and 90 respectively, thereby reversing the connection of these wires with the mains L^2 and L^3 and causing the motor 21 to move the cage 15 in a down direction.

When the elevator units are to be operated jointly, the counterweights 31 and 32 are connected by the locking members 56, the gates 19 are raised, and the interlocking switches are thrown into the positions illus-

trated in full outline in Figure 9. In practice, the interlocking switches, excepting switches 64, 65 and 79 are all controlled by a single actuator, and are, therefore, operated together to place the elevator unit either in condition for independent operation or in condition for joint operation.

Upon connecting the counterweights 31 and 32, the switch 65 is opened thereby preventing independent operation of the cages 15 and 16, and the switch 64 is closed thereby permitting joint operation of the cages as will be hereinafter described.

Upon raising the gates 19 the switches 79 are opened thereby preventing independent operation of the cages.

Upon throwing the interlocking switches into position for joint operation of the cages, the switches 65 and 79 are shunted by the interlocking switch 80 thereby permitting joint operation when the gates 19 are up and the switch 65 is open. The controller 70' is shunted and the safety devices and fuses in the wires 78 and 78' are connected in series in the wire 78 by the switches 83 and 83' and an interlocking switch 115. The switch 83' is connected by a wire 116^a through the switch 64 to the controller 70. The switch 64 thus controls the circuit through the controller 70, and must be closed to permit joint operation of the elevator units. This necessitates connecting the counterweights 31 and 32.

Since the controller 70' is rendered inoperative, the wires 84' and 111' are connected by wires 116 and 117 leading through interlocking switches 118 and 119 to the wires 84 and 111 respectively, to connect the coils 85' and 85 in parallel to the contact 72 and the coils 112' and 112 in parallel to the contact 71.

The wires 86 and 86' leading from the coils 85, 85', 112 and 112' to the main L³ are connected by an interlocking switch 120, and the safety devices 87 and 87' and the fuse 89 in said wires are connected in series by the interlocking switches 88 and 88' and an interlocking switch 121. It will be evident that upon movement of the controller 70 into engagement with the contact 72, the switches 73 and 73' will be simultaneously actuated to effect a movement of the cages 15 and 16 in an up direction, and that upon movement of the controller 70 into engagement with the contact 71, the switches 74 and 74' will be simultaneously actuated to effect a down movement of the cages. All of the safety devices in both elevator units are connected into the joint system.

To obtain a like acceleration of the two motors 21 and 22, the accelerating switches 76 and 77, and 76' and 77' are placed under the control of the time switches 102 and 103 by connecting the coil 104 through a wire 122 and a switch 123 to the coil 104'

to shunt the switch 102', and connecting the coil 108 through a wire 124 and a switch 125 to the coil 108' to shunt the switch 103'.

It will be evident that I have provided a highly advantageous elevator comprising two independent elevator units which can be operated separately or which can be easily and quickly converted into a single system. By connecting the counterweights for joint movement, the cages can be driven through a substantial distance at exactly the same level and no breakage or injury will result if one cage should move at a greater speed than the other. In general the elevator is extremely simple in construction, and is highly efficient in operation.

I claim as my invention:

1. An elevator having, in combination, two independent elevator units each of which comprises a cage, a counterweight, traction means, and a set of control circuits for said means, a hatchway for said cages and said counterweights, means for connecting said counterweights, and means for converting said sets of control circuits into a single system under one control.

2. An elevator having, in combination, two elevator units each of which comprises a cage, a counterweight, driving means for said cage, and a set of control circuits for said means, a hatchway for said cages, means for connecting said counterweights, and means for connecting said sets of circuits to convert them into a single system for operating said cages jointly, said last mentioned means including a pair of interlocking switches controlled by said means for connecting said counterweights.

3. An elevator having, in combination, two independent elevator units each of which comprises a cage, a counterweight, means for driving said cage and counterweight, and a set of control circuits including a car switch, a hatchway for said cages, and means for connecting said sets of control circuits to convert them into a single system under the exclusive control of one of said car switches for operating said cages jointly at the same level and at a uniform speed.

4. An elevator having, in combination, two elevator units, each of which comprises a cage, a counterweight, means for driving said cage, and a set of control circuits including a car switch, and each of which is independently operable, a hatchway for said cages, means for connecting said counterweights and means for connecting said sets of control circuits to convert them into a single system under the control of one of said car switches for the joint operation of the cages, the connection of said counterweights serving to maintain said cages to the same level throughout their joint movement.

5. An elevator having, in combination,

two independent elevator units, each of which comprises a cage, a counterweight, means for driving said cage, and control circuits for said driving means, said counterweights being mounted to move closely past each other, a single hatchway in which said cages are disposed, and means for connecting and disconnecting said counterweights to place said elevator units in a condition for joint operation or in a condition for independent operation respectively.

6. An elevator having, in combination, two independent elevator units, each of which comprises a cage, a counterweight, means for driving said cage, and control circuits for said driving means, means for connecting corresponding parts of the two units to place said units in a condition for joint operation with said cages moving at the same level, and means for connecting said control circuits into a single system for synchronizing the operation of said driving means.

7. An elevator having, in combination, two independent elevator units each of which comprises a cage, a counterweight, and means for driving said cage, and means for connecting corresponding parts of said two units to place them in condition for joint operation in which the cages are maintained at the same level throughout their joint movement.

8. An elevator having, in combination, two elevator units each of which comprises a counterweight, a cage, and driving means therefore, and means connecting said counterweights to move as a unit, thereby serving to cause said cages to move jointly, and to maintain said cages at the same level throughout such joint movement.

9. An elevator having, in combination, two elevator units, each of which comprises a cage, a counterweight, and means for driving the same, a hatchway for said cages and said counterweights, and means carried by one of said counterweights for connecting said counterweights together to move as a unit, thereby maintaining said cages at the same level for joint movement.

10. An elevator having, in combination, two elevator units each comprising a cage, a counterweight, means for driving said cage, and a set of control circuits for said driving means, a hatchway for said cages and said counterweights, means for connecting the counterweights to cause them to move as a unit and thereby maintain said cages at the same level for joint movement, and interlocking means forming part of said sets of control circuits and controlled by said last mentioned means for preventing joint operation when the counterweights are disconnected and for preventing independent operation when the counterweights are connected.

11. An elevator having, in combination, two elevator units, each of which comprises a cage, a counterweight, means for driving said cage, and a set of control circuits for said driving means, a single hatchway for said cages, and means for connecting said counterweights to move as a unit, thereby serving to maintain said cages at the same level throughout their joint movement in said hatchway.

12. An elevator having, in combination, two elevator units, each of which comprises a cage, a counterweight, means for driving said cage, and control circuits for said means, said cages being supported for movement in closely spaced paths, gates in the adjacent sides of said cages, switches controlled by said gates and forming part of the control circuits of each unit, said switches preventing independent operation of said units when said gates are open, and means for mechanically connecting said units for joint operation.

13. An elevator having, in combination, two elevator units, each of which comprises a cage, a counterweight, means for driving said cage, and control circuits for said means, said cages being supported for movement closely past each other, gates in the adjacent sides of said cages, switches controlled by said gates and forming part of said control circuits of each unit, said switches preventing independent operation of said units when said gates are open, and means for connecting said counterweights to move as a unit to maintain said cages at the same level throughout their joint movement.

14. An elevator having, in combination, two elevator units, each of which comprises a cage, a counterweight, means for driving said cage, and control circuits for said means, gates in the adjacent sides of said cages, switches controlled by said gates and forming part of said control circuits of both units, said switches preventing independent operation of said units when said gates are open, means for connecting said units to permit joint operation thereof, and means for connecting said counterweights to move as a unit to maintain said cages at the same level throughout their joint movement.

15. An elevator having, in combination, two elevator units each of which comprises a cage, a counterweight, and means for driving said cage, and a set of control circuits for said driving means, a hatchway in which said cages are mounted for movement side by side, gates in the adjacent sides of said cages, switches controlled by said gates and forming part of each set of control circuits, said switches acting to prevent independent operation of said units when said gates are open, means for connecting said counterweights, and interlocking switches controlled by said connecting means and form-

ing part of said sets of control circuits, said interlocking switches serving to prevent independent operation of said units when said counterweights are connected and serving to prevent joint operation of said units when said counterweights are disconnected.

16. An elevator having, in combination, two elevator units each of which comprises a cage, a counterweight, means for driving said cage, and a set of control circuits for said driving means, means for connecting said counterweights, and switch means controlled by said connecting means and forming part of each set of control circuits, said switch means serving to prevent independent operation of said units when said counterweights are connected.

17. An elevator having, in combination, two elevator units each of which comprises a cage, a counterweight, means for driving said cage, a set of control circuits for said driving means and including a car switch and a series of safety devices, means for connecting said counterweights, switch means controlled by said connecting means and forming part of each set of control circuits, said switch means serving to prevent independent operation of said units when said counterweights are connected, and to prevent joint operation of said units when said counterweights are disconnected, and means including a series of interlocking switches for connecting various parts of said two sets of control circuits to place both sets under the control of one car switch, and to connect the safety devices of both sets in the joint system.

18. An elevator having, in combination, two elevator units each of which comprises a cage, a counterweight, means for driving said cage, and a set of control circuits for said driving means and including a car switch and a series of safety devices, means for mechanically connecting corresponding parts of the elevator structure of the two units, switch means controlled by said connecting means and forming part of each set of control circuits, said switch means serving to prevent independent operation of said units when said parts are connected, and to prevent joint operation of said units when said parts are disconnected, and means including a series of interlocking switches for connecting various parts of said two sets of control circuits to place both sets under the control of one car switch, and to connect the safety devices of each set in the joint system.

19. An elevator having, in combination, two elevator units each of which comprises a cage, a counterweight, means for driving said cage, a set of control circuits for the driving means and a series of safety devices, means for mechanically connecting corre-

sponding parts of the elevator structure of the two units, switch means controlled by said connecting means and forming part of each set of control circuits, said switch means serving to prevent independent operation of said units when said parts are connected, and to prevent joint operation of said units when said parts are disconnected, and means including a series of interlocking switches for connecting various parts of the sets of control circuits to convert both sets of control circuits into a single system including the safety devices in both sets.

20. An elevator having, in combination, two elevator units each of which comprises a cage, a counterweight, means for driving said cage, and a set of control circuits for the driving means, means for mechanically connecting corresponding parts of the elevator structure of the two units, and switch means controlled by said connecting means and forming part of each set of control circuits, said switch means serving to prevent independent operation of said units when said parts are connected, and to prevent joint operation of said units when said parts are disconnected.

21. An elevator having, in combination, two elevator units, each of which comprises a cage, a counterweight, means for driving said cage, and a set of control circuits for said driving means and including a set of safety devices, means for connecting said counterweights, and means for connecting various parts of the two sets of control circuits to convert them into a single system including said safety devices.

22. An elevator having, in combination, two elevator units each of which comprises a cage, a counterweight, means for driving said cage, and a set of control circuits for said driving means, means for connecting said counterweights to connect said units for joint operation, and means for connecting parts of said sets of control circuits to convert said sets into a single system.

23. In a double unit elevator, in combination, two counterweights adapted to be positioned side by side, each counterweight having a vertically adjustable head, and locking means in one head adapted to be moved into engagement with the other head to connect said counterweights.

24. In a double unit elevator, in combination, a pair of counterweights disposed for movement in closely spaced parallel paths, each counterweight having a head, a pair of locking members pivotally mounted in one of said heads and being adapted to be swung into engagement with the other head when said counterweights are positioned side by side, gear means for actuating said locking members, and a pair of switches one of

- which is controlled by each locking member.
25. In a double unit elevator, in combination, a pair of counterweights adapted to be positioned side by side, a pivotal locking member mounted on one counterweight, and means for pivoting said locking member into engagement with the other counterweight when said counterweights are positioned side by side.
- 10 26. In a double unit elevator, in combination, two counterweights adapted to be positioned closely together, a pair of locking members pivotally mounted in one of said counterweights and adapted to engage the other of said counterweights to connect the two, and gear means for actuating said members.
- 20 27. In a double unit elevator, in combination, a pair of counterweights adapted to be positioned in closely spaced relation, a locking member pivotally mounted in one of said counterweights and adapted to be moved into engagement with the other of said counterweights to secure said counterweights together, and gear means for actuating said pivotal locking member in either direction to engage or disengage said counterweights.
- 25 28. In a double unit elevator, in combination, two counterweights adapted to be positioned closely together, each counterweight having a head, a pair of locking members pivotally mounted in one of said heads and adapted to be moved into engagement with the other of said heads to lock said counterweights together, each locking member having a gear quadrant, and a worm gear meshing with said gear quadrants and adapted to actuate them in either direction to lock or unlock said counterweights.
- 30 29. In a double unit elevator, in combi-

nation, two counterweights, one for each unit, and means for mechanically connecting said counterweights.

30. In a double unit elevator, in combination, a pair of counterweights adapted to be 45 mounted side by side, a head adjustably mounted in each counterweight, locking means in one head adapted to be moved into engagement with the other head to lock said counterweights together, and means for actuating said locking means.

31. An elevator having, in combination, a hatchway, two elevator cages mounted in said hatchway for adjacent movement side by side, two counterweights one for each 55 cage mounted in said hatchway on vertical guide rails, said rails being arranged in two parallel and closely spaced sets, means for connecting said counterweights, and means for driving said cages independently when 60 said counterweights are disconnected, and jointly when said counterweights are connected.

32. A double unit elevator having, in combination, a hatchway, two cages mounted in 65 said hatchway for adjacent movement, a pair of counterweights mounted in said hatchway, means for connecting said counterweights, and means for driving said cages jointly or independently. 70

33. A double unit elevator having, in combination, a hatchway, two cages mounted in said hatchway, a pair of counterweights one for each cage, means for mechanically connecting corresponding parts of the elevator 75 structure of each unit, and means for driving said cages jointly or independently.

In testimony whereof, I have hereunto affixed my signature.

JAMES DUNLOP.
